FLUORESCENT LAMP HOLDER

David Lane, Philadelphia, Pa., assignor to Progress Manufacturing Company, Inc., Philadelphia, Pa., a corporation of Pennsylvania

Application April 8, 1950, Serial No. 9,068

Term of patent 14 years

(Cl. D48—23)

To all whom it may concern:

Be it known that I, David Lane, a citizen of the United States and a resident of Philadelphia, county of Philadelphia, State of Pennsylvania, have invented a new, original, and ornamental Design for a Fluorescent Lamp Holder, of which the following is a specification, reference being had to the accompanying drawings, forming a part thereof, wherein:

Figure 1 is a perspective view of a fluorescent lamp holder, showing my new design;

Figure 2 is an end elevational view thereof as viewed from the line 2—2 of Figure 4;

Figure 3 is a front elevational view thereof as viewed from the line 3—3 of Figure 4; and

Figure 4 is a side elevational view thereof.

I claim:

The ornamental design for a fluorescent lamp holder, substantially as shown.

DAVID LANE.
